(57) CLAIM

The ornamental design for a vest, as shown and described.

DESCRIPTION

FIG. 1 is a front view of a vest showing my new design;

FIG. 2 is a second front view thereof;

FIG. 3 is an alternate right side view thereof;

FIG. 4 is an alternate rear view thereof;

FIG. 5 is an alternate left side view thereof; and,

FIG. 6 is an alternate top view thereof.

The broken lines shown in the drawings show stitching and are a part of the claimed design.
